UNITED STATES PATENT OFFICE

VELICO H. MINCHEVLY, OF CLINTON, IOWA

STOVE FOR SIRUP BOILING

Application filed June 17, 1929. Serial No. 371,648.

The object of this invention is to provide an improved construction for a stove particularly adapted for use in the boiling down of sirup and for similar purposes.

5 A further object of the invention is to provide an efficient and economical construction for a stove of large capacity, and which is of especially rugged and durable construction so that it may be continuously operated for 10 a considerable period of time.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a plan view of my improved 20 stove, partly in section.

Figure 2 is a side elevation of the same, partly in section.

Figure 3 is a cross section on the line 3—3 of Figure 2.

25 Figure 4 is a cross section on the line 4—4 of Figure 2.

Figure 5 is a detail sectional view, illustrating the method of providing a finished construction at the base of the stove.

30 In the construction of my improved stove, I employ a base plate 10 on which is mounted the housing. The housing is composed primarily of a top plate 11, side walls 12 and end walls 13. The side walls and end walls are 35 formed at their lower margins with outturned flanges 14, which rest on marginal portions of the base plate 10 and are secured thereto by bolts or rivets 15.

Within the lower part of the housing is a 40 supporting plate 16 having downturned marginal flanges 17 terminating in inturned flanges 18. The flanges 18 rest on the base plate 10 and are secured thereto by rivets or the like 19.

45 Marginal portions of the base plate 10 are turned upwardly to form flanges 20 within which the base flanges 14 of the walls fit. The flanges 14, rivets 15 and upper edges of the flanges 20 are covered by finishing strips 50 21 held in place by screws or the like 22.

The end portions of the housing are extended upwardly to form smoke boxes 23 and 24 and said smoke boxes are provided with suitable flues 25 and 26 respectively.

Within the housing and preferably extending throughout the greater portion of the length thereof is a fire box structure including a bottom wall 27 resting on the supporting plate 16, and side walls 28 arranged just within the housing walls 12. At the bottom of the fire box structure an ash pit 29 is formed, and centrally above this is a grate 30. Extending upwardly from opposite sides of the grate are inclined fire box walls 31 which are connected at their upper ends with the side walls 28. The fire box walls 31 may slope to any desired degree to suit particular purposes, such as for different kinds of fuel.

Access may be had to the upper portion of 70 the housing through any desired number of openings closable by hinged fuel doors 32.

Access may be had to the lower portion of the housing through any number of suitably located openings communicating with the 75 ash pit 29 and closable by hinged ash doors 33.

Those portions between the fire box walls 31 and side walls 28 constitute ovens 34 to which access may be had through door openings closable by hinged doors 35. The ovens are here shown as provided with horizontal partitions 36. Flue openings 37 are formed through lower portions of the fire box walls 31, normally closed by means of 80 85 slideable damper valves 38.

A cover plate 39 is provided for that portion of the housing between the smoke boxes 23 and 24. The cover plate 39 is of less width than the top wall 11 of the housing and is 90 fitted within a rabbet or depression formed in the upper surface of said top plate.

The top plate 11 of the housing is formed with a plurality of openings 40 and the cover plate is formed with a plurality of larger 95 openings 41. The openings 40 may be placed in groups arranged beneath or with special relation to the larger openings 41 of the members 39, as shown particularly in Figure 100 1.

Juices or other substance to be boiled may be placed in suitable containers which are mounted upon the cover plate 39 and a fire is built and maintained within the fire box 5 of the housing by means of fuel placed upon the grate 30.

The fire box communicates at its ends with the smoke boxes 23 and 24, as indicated in Figure 3, so that products of combustion may 10 pass to the smoke boxes and then out through the flues 25 and 26.

At opposite sides of each smoke box 23 and 24 are placed reservoirs 42 and 43 adapted to contain water which is heated by fire in the 15 stove. Each reservoir is provided with a removable cover 44. Access may be had to the reservoirs through openings in the top of the housing at the sides of the smoke boxes. These openings are provided with removable 20 covers 45.

Removable ash pans 46 may be placed in the pit 29 for convenience in receiving and removing ashes which fall through the openings of the grate 30.

25 It is to be understood that my improved stove may be made of any desired size and proportions and that various modifications and changes may be employed within the scope of the appended claims without departing 30 from the real spirit of my invention.

I claim as my invention:

1. A stove of the character described, comprising a housing, the top wall of said housing being formed with a rabbeted depression 35 and also being formed with a plurality of relatively small openings therethrough, a cover plate mounted in said depression, said cover plate being formed with relatively large openings therethrough, each registering with 40 a group of the smaller openings in the housing top wall, and a grate in the lower part of said housing.

2. A stove of the character described, comprising a base plate, a housing having walls 45 formed at their lower margins with outturned flanges resting on and secured to marginal portions of said base plate, a supporting plate having downturned marginal flanges terminating in inturned flanges resting on and 50 secured to said base plate, and a fire box structure within said housing resting on said supporting plate.

3. A stove of the character described, comprising a base plate, a housing having walls 55 formed at their lower margins with outturned flanges resting on and secured to marginal portions of said base plate, a supporting plate having downturned marginal flanges terminating in inturned flanges resting on and 60 secured to said base plate, and a fire box structure within said housing resting on said supporting plate, said base plate being formed with peripheral upturned flanges within 65 which the base flanges of the housing wall snugly fit.

4. A stove of the character described, comprising a base plate, a housing having walls formed at their lower margins with outturned flanges resting on and secured to marginal portions of said base plate, a supporting plate 70 having downturned marginal flanges terminating in inturned flanges resting on and secured to said base plate, and a fire box structure within said housing resting on said supporting plate, said base plate being formed with peripheral upturned flanges within 75 which the base flanges of the housing wall snugly fit, together with finishing strips mounted on and covering the base flanges of the housing walls and the upper edges of the upturned flanges of the base plate.

5. A stove of the character described, comprising a housing having a top wall, a cover plate mounted substantially parallel with said top wall, one of said parallel members being formed with a plurality of openings therethrough, the other of said members being formed with groups of relatively smaller openings, each group being in substantial registry with one of the openings of the first 80 mentioned member, and a grate in the lower part of said housing.

Des Moines, Iowa, April 8, 1929.
